ANTI-SPINNING CONSTRUCTION FOR ROTARY DIAL ADDERS

Elmer G. Kesling, Richmond Heights, Mo.

Application March 12, 1956, Serial No. 571,103

15 Claims. (Cl. 235—74)

The present invention relates generally to portable calculators, and more particularly to a pocket calculator incorporating a novel anti-spinning construction which prevents unintended movement of dials during periods when they are released from normal detent control.

Calculators having a multiplicity of rotary dials, including separate dials for units, tens, hundreds, etc., are widely known and have a basic mode of operation which is generally well-understood. It is with a specific requirement of the basic mode of operation that the present invention is involved, namely, the requirement for release from normal detent control of dials of higher number than the one operated so as to enable the released dials to be appropriately indexed in accordance with the demands of the particular computation.

Whereas, normally, the several dials of the pocket calculator here considered are maintained against inadvertent rotation by means of efficient detent mechanism, it has been found that the necessity for releasing certain of these dials for the purpose above-mentioned leaves them momentarily susceptible to uncontrolled rotation. For example, an indexing pulse from an adjacent dial may be of sufficient force to cause the indexed dial to spin past the intended position, which will, of course, produce an error in the computation.

It is an object of the present invention, therefore, to provide a novel anti-spinning mechanism which maintains interlocked cooperation between adjacent dials so as to inhibit the "spinning" of a dial as it is indexed.

It is another object of the present invention to provide a novel mechanism for controlling the rotation of one dial through an interlocking connection with an adjacent dial.

It is another object of the invention to provide a novel anti-spinning mechanism which incorporates a rockable lever adapted to cooperate with adjacent rotary dials.

It is another object of the invention to provide a pocket calculator which incorporates novel anti-spinning mechanism for controlling the movement of released dials.

The foregoing, along with additional objects and advantages, will be apparent from the following description of a specific embodiment of the invention taken with the accompanying drawings illustrating the same. In the drawings:

Figure 1 is a plan view of a pocket calculator incorporating the teachings of the present invention;

Figures 2 and 3 are vertical longitudinal sections taken substantially along the lines 2—3 of Figure 1, but drawn to an enlarged scale;

Figure 4 is a horizontal plan view of the calculator similar to Figure 1, but with the cover removed and with certain parts and portions of parts removed and sectioned in a manner to indicate clearly the assembled relation of parts in the device;

Figure 5 is a horizontal cross-sectional view drawn to an enlarged scale and showing a fragmentary portion of the calculator;

Figure 6 is a fragmentary vertical section taken generally along the line 6—6 of Figure 5;

2

Figure 7 is a vertical elevation of a removed dial;
Figure 8 is a horizontal bottom view of the removed dial;

Figure 9 is a horizontal plan view of a removed detent plate drawn to reduced scale;

Figure 10 is an enlarged fragmentary vertical section showing the right-hand end of a calculator incorporating a modified arrangement of the present invention;

Figure 11 is a fragmentary horizontal sectional view showing a portion of the right-hand end of the calculator of Figure 10 with its cover removed;

Figure 12 is a fragmentary vertical section taken generally along the line 12—12 of Figure 11;

Figure 13 is a horizontal bottom view of a removed dial of the type employed in the calculator of Figure 10;

Figure 14 is a fragmentary vertical section taken along the line 14—14 of Figure 13; and

Figure 15 is a bottom plan view of an idler gear.

Referring to the drawings more particularly by reference numerals, and directing attention first to Figures 1 through 9, 20 indicates generally a calculator incorporating the teachings of the present invention. In its broad aspects, the calculator 20 includes a case 21 comprising a base 22 and a cover 24, dial members 27 for units, tens, hundreds, etc., a detent 28 and detent spring 29, idler gears 30, and rocking levers 32. Preferably, the components of the calculator 20 are made of plastic material, with the exception of the spring 29 employed for the detent 28. Conventional cross-hatching is used in the drawings in the interest of clarity of illustration.

The base 22 is generally rectangular in form and includes a bottom 40, side walls 41 and 42 and end walls 43 and 44. Extending upwardly from the bottom 40 are equally spaced integral posts 45 which rotatably support the dial members 27, as illustrated. The posts 45 slope slightly in the longitudinal direction of the base 22, but are at right angles to the latter when viewed lengthwise. Each post 45 has a well 46 for a purpose which appears below. There are six posts 45 in the present calculator

20, although a greater or a lesser number may be used, and to one side of each, except the right-hand one, viewing Figure 3, is an integral post 48 having an annular reduced neck 49 inset by a sloping shoulder which rotatably receives a reversing or idler gear 30, as illustrated.

Referring to Figures 4, 5 and 6, spaced to the right and above each post 48 there is an integral post 50 having an offset annular reduced neck 51 for pivotally receiving a rocking lever 32, as illustrated. Finally, in the upper right hand corner of the bottom 40 is an integral post 53 for anchoring the detent spring 29. An elongated recess 54 is formed in the bottom 40 for accommodation of the detent spring 29.

Each dial member 27 includes an upper disc dial portion 58, a lower disc portion 59 of smaller diameter than the disc portion 58 having a transfer finger 60, a cam portion 61 provided with a plurality of angularly spaced notches 62 and with one elongated notch 63 as clearly illustrated in Figure 8, and a gear portion 64 comprising ten teeth 65 spaced equidistantly, as also illustrated in Figure 8. A cylindrical opening 66 extends through the dial member 27 by means of which it is freely rotatably mounted upon its respective post 45 (Figures 2 and 3.)

Adjacent the periphery of the upper face of the dial portion 58 are equi-spaced counterclockwise numbers 1 through 9, and 0, and midway between and inwardly of each pair of numbers is a well 67 for receiving a stylus or pencil point. Preferably, the dial members 27 are of integral construction. Note that an idler gear 30 engages each gear portion 64, except the right-hand one, and is engageable at its right side by a transfer finger 60. The illustrated detent 28 is in the form of a flat plate having elongated openings 68 therein, each of

which is large enough to receive a gear portion 64 and an idler gear 30 in a manner to permit free longitudinal movement of the detent 28. Elongated openings 69 are provided which receive the several posts 50 above mentioned. The elongated openings enable the detent 28 to have limited reciprocal movement longitudinally of the calculator 20, and it is preferred that the lateral width of the two elongated openings nearest each end of the detent 28 be sized for guiding the reciprocating movements of the member 28. Further, it is preferred that the intermediate openings 69 be of ample size to clear the associated posts 50 so as to avoid any possibility of frictional binding at these points.

Referring further to the detents 28, a plurality of detent angles 70 are formed, one each for engagement with the upper part of the gear portion 64 of the respective dial members 27. It is to be noted that the detent angles 70 are at an increasing angle from right to left, as clearly illustrated in Figure 9, which is a relationship originally disclosed in applicant's Patent No. 2,588,539.

Referring to Figures 4 and 5, the detent 28 is biased into engagement with the gear portions 64 by the detent spring 29, one end of which is hooked into the end wall of the rightmost elongated opening 69 and the other end of which is secured to the post 53 formed integral with the bottom 40 of the base 22.

As best shown in Figure 6, the posts 50 have flat surfaces 72 upon which the rocking levers 32 rest. This surface 72 is normal to the axis of the post 50, and the pivot portion 51 extends upwardly therefrom to pass through a hole 73 in the lever 32. The lever 32 is generally plate-like as clearly shown in Figures 5 and 6, except for an integral upstanding projection or tooth 74 provided at the right-hand end and a generally similar integral tooth 75 provided at the left-hand end. Directing attention first to the tooth 74, it is clear from Figure 5 that this element of the lever 32 is formed for engagement with the notches 62 and 63 formed in the cam portion 61 of the associated dial 27. The tooth 75, on the other hand, is positioned and formed for engagement with the idler gear 30 which is immediately to the left of the particular dial member 27. As illustrated, both the tooth 74 and the tooth 75 are provided with angularly related faces which engage in the notches 62 and 63 in the case of the tooth 74 and between the teeth of the idler gear 30 in the case of the teeth 75. In either case, it is apparent that rotation of an element with which a tooth 74 or a tooth 75 may be engaged is effective to cause displacement of the engaged tooth through a camming action against an angular face of the tooth. As is clear from Figure 5, however, the positional relationship of the teeth 74 and 75 to each other is such that one or the other must be interlockingly engaged with its respective rotatable member, either the dial 27 or the idler gear 30, in order for the other rotatable member to be rotated.

The cover 24 has a top 85, side walls 86 and 87, and end walls 88 and 89. The top 85 is formed with equi-spaced arcuate slots 92, adjacent each of which is a small window opening 93. The window openings 93 enable the results of computation to be viewed. Each arcuate slot 92 defines a disc portion 94 which is joined to the rest of the top 85 by a neck 96. Each disc portion 94 has an integral frusto-conical post 95 depending therefrom which extends into the well 46 of the respective post 45 to align the cover 24 and to provide anchoring support for the disc portion 94. Each disc portion 94 has numbers 1 through 9 adjacent the periphery in clockwise relation opposite nine of the ten wells 67 (Figure 1). It will also be noted that numerals 1 through 9 are formed on the top 85 counter-clockwise along the outer edge of each arcuate slot 92 opposite nine of the wells 67. The cover 24 is cemented to the base 22.

The idler gears 30 have eight teeth in the present embodiment, although they may have a different number.

The gear portions 64 of the dial members 27 each have ten teeth so that a transfer of accumulated sums takes place at each revolution in accordance with our arithmetical system.

Figures 10 through 15 illustrate a modified arrangement of the present invention in the form of a calculator 100. Inasmuch as the calculator 100 is basically similar to the previously described calculator 20, corresponding elements in the calculator 100 have been given the same reference numeral that was originally assigned to the elements of the calculator 20. In the calculator 100, however, these numerals are primed in order to distinguish between the two arrangements.

Considering first the case 21' of the calculator 100, the top 24' is in all respects identical with the previously described top 24 of the calculator 20. The base 22' while generally similar to the base 22 differs in minor respects therefrom. One difference is in the posts 48', which are formed with the inset portions 49' extending almost the full length of the posts. As is clear from Figure 10, the portions 49' are adapted to receive an idler gear 30' having much greater depth than the idler gear 30 of the calculator 20. Another difference, shown clearly in Figures 11 and 12, is in the relocation of the posts 50' as compared to the posts 50, and the elimination of the pivot portions therefrom. Posts 51' are, on the other hand, provided at points corresponding to the location of the portions 51 in the calculator 20. It will be understood that there is a post 51' disposed above and to the right of each idler gear 30'. The height of the posts 51' are, as illustrated in Figure 12, such as to provide support for the detent 28' disposed thereabove. With the detent 28' elevated to a position above the rocking levers 32', there is of course no requirement for a spring trough in the base 40'.

The dial member 27', illustrated in Figures 13 and 14, does not include a cam portion as does its corresponding member 27 of the calculator 20. The gear portion 64' has nine standard teeth 65' and one tooth 102 having an upper section 103 of standard tooth dimension and a lower section 104 wherein the tooth is of shortened depth.

The idler gears 30' also have different upper and lower sections, there being an upper section comprising tooth portions 105 of standard dimension and lower sections comprising tooth portions 106 wherein the teeth have shorter depth.

The rocking levers 32' are generally similar to the above-described rocking levers 32, except that the levers 32' do not have upstanding cam portions. In place of these, the levers 32' have the plate-like body extended to form cam projections 74' and 75' shaped as clearly illustrated in the plain view of Figure 11. Once more, it will be observed that the shape of the cams 74' and 75' are such as to enable them to enter between adjacent teeth of the dial member 27' and the idler gear 30', respectively, but to be urged out of such relationship when these latter members are rotated.

Operation

It is obvious from the foregoing that the calculators 20 and 100 function in respect to addition, subtraction, and the like, in the same manner as the calculator shown in the applicant's above-mentioned Patent No. 2,588,539. That is, to add figures in either the calculator 20 or the calculator 100, units are accumulated on the right hand or units dial member 27, or 27', tens on the dial member 27 or 27' immediately to the left thereof, hundreds on the next dial member 27 or 27', etc. As clearly set forth in the above-mentioned patent, the detent 28 or 28' functions in a manner to free or to release for rotation each dial 27 or 27' to the left of the one which is manually rotated, while, at the same time, continuing to impose restraint against rotation of dial members 27 or 27' to the right of that which is manually rotated. The neces-

sity for releasing the dial members 27 or 27' to the left is of course due to the fact that one or more of the dials may be required to be rotated by the well-understood operation of the transfer fingers 60 or 60' and the idler gears 30 or 30' in accumulating multiples of ten on the next higher dial. As previously mentioned, however, the very fact that certain of the dials are thus released from restraint against rotation makes them susceptible to rotation beyond the intended single position. In other words, vigorous rotative impetus applied to the manually rotated dial may be transferred with sufficient force to an adjacent dial to cause the latter to rotate past the intended position. The levers 32 and 32' of the present invention serve not as positioning devices to position rotatable elements, but to prevent this inadvertent rotation past the intended point.

Considering first the arrangement of the calculator 20, it is clear from Figures 4 and 5 that each rocking lever 32 cooperates directly with a dial member 27 and with the idler gear 30 immediately to the left thereof. Inasmuch as each idler gear 30 is continually meshed with the gear portion 64 of the next dial member 27, it may obviously be considered that each rocking lever 32 provides interlocking cooperation between a pair of adjacent dial members 27.

Directing attention now to the enlarged view of Figure 5, it is clear that both of the illustrated dial members 27 are restrained against inadvertent rotation due to the insertion of the detent points 70 between adjacent pairs of teeth of the gear portions 64. Assuming, however, that the right hand dial member 27 is now manually rotated, the detent 28 will be biased toward the left so that the left hand member 27 will be released each time a tooth 65 of the right hand member 27 passes the associated detent point 70. If it be assumed that the right hand dial member 27 is turned clockwise from the position illustrated in Figure 5, it is clear that the cam projection 74 will be biased out of the notch 62, and that the cam projection 75 will thus necessarily be inserted between two teeth of the idler gear 30. This will prevent rotation of the latter and hence also of the left hand dial member 27 during the time that the right hand member 27 is rotated one position, or until the next notch 62 is in position to receive the cam projection 74. When this latter condition is satisfied, the rocking lever may again be rocked so as to withdraw the cam projection 75 from between the teeth of the idler gear 30, but at this time, it will be noted that the detent point 70 will have been reinserted between two teeth 65 of the right hand member 27.

From the foregoing, it will be seen that, for the most part, the right hand dial member 27 may be rotated freely with positive assurance against inadvertent rotation of the dial member 27 to its left. However, it is necessary under certain conditions that the rotative movement of the right hand member 27 be transferred through the action of the transfer finger 60 and the idler gear 30 to the left hand dial member 27. This condition is apparent from Figure 5 upon the assumption that the right hand member 27 is to be moved counterclockwise. Such movement of the right hand member 27 will cause the transfer finger 60 to engage one of the teeth on the idler gear 30, causing both it and the left hand member 27 to rotate.

As previously mentioned, any rotation of the right hand member 27 biases the detent member 28 to the left so as to withdraw the detent point 70 from between the teeth 65 of the left hand dial member 27. Also, it will be noted that counterclockwise movement of the right hand dial member 27 from the position illustrated in Figure 5 will cause the cam projection 74 again to be biased from the notch 62, but enables it to be immediately received in the special elongated notch 63. The rotative impetus applied to the idler gear 30 by engagement of the transfer finger 60 therewith biases the cam projection 75 out from be-

tween the teeth of the gear 30 and enables the left hand dial member 27 to move under the influence of the finger 60 one position. Continued counterclockwise movement of the right hand dial member 27 moves the notch 63 past the cam projection 74 and the previously described interlocked cooperation between the adjacent dial member 27 is immediately reasserted to prevent passage of the next tooth. It will be noted that the present invention provides for continuous interlocking connection between adjacent dial members through at least one of three elements, namely, the detent member 28, the rocking lever 32, or the transfer finger 60. The interlocked relationship of the dials which exists even during operation of the calculator by virtue of the levers 32 prevents the dials from ever jiggling out of position. This eliminates, incidentally, the need for brake springs to dampen the rotation of dials as shown in my Patent No. 2,588,539.

Considering now the arrangement of the calculator 100, it is obvious that the general mode of operation is the same as that of the calculator 20. Instead of operating in conjunction with a special cam portion, however, the cam 74' operates between the teeth 65' of the dial member 27'. Thus, from Figure 11 it is apparent that the lever 32' functions similar to its counterpart 32 in the calculator 20. When the right hand dial member 27' is rotated so as to engage the transfer finger 60' with the idler gear 30' the special tooth portion 104 of shortened depth will enable the lever 32' to be pivoted clockwise sufficiently to enable withdrawal of the cam 75' from between the shortened teeth 106 of the idler gear 30'.

Clearly, there has been provided an anti-spinning construction and a modification thereof which fulfill the objects and advantages sought therefor.

It is understood that the foregoing description and the accompanying drawings have been given by way of illustration and example. It is also to be understood that changes in form of the elements, rearrangement of parts, and the substitution of equivalent elements, which will be obvious to those skilled in the art, are contemplated as within the scope of the present invention, which is limited only by the claims which follow.

What is claimed is:

1. In a calculator, in combination, a case, a plurality of dial members rotatably mounted in said case, and means movably mounted adjacent said dial members cooperative therewith to effect computation, said means including primary detent means for releasably retaining said dial members in positions of rest and secondary detent means for preventing inadvertent rotation of dials during periods of release from said primary detent means.

2. In a calculator, in combination, a case, a plurality of dial members rotatably mounted in said case, and means movably mounted adjacent said dial members cooperative therewith to effect computation, said means including a detent member for interlocking connecting adjacent dial members in positions of rest and being movable upon rotation of one dial member to release an adjacent dial member for purpose of computation, and an interlocking member in addition to said detent member for preventing rotation of said released dial member other than as required for computation.

3. In a calculator, in combination, a case, a plurality of dial members rotatably mounted in said case, and means movably mounted adjacent said dial members cooperative therewith to effect computation, said means including detent means for interlocking connecting adjacent dial members in positions of rest and being movable upon rotation of one dial member to release an adjacent dial member for purpose of computation, and means in addition to said detent means for preventing rotation of said released dial member other than as required for computation, said latter means including a movable member adapted for selective mutually exclusive interlocking connection with each of said adjacent dial members.

4. In a calculator, in combination, a case, a plurality

of dial members rotatably mounted in said case, and means movably mounted adjacent said dial members cooperative therewith to effect computation, said means including detent means for interlockingly connecting adjacent dial members in positions of rest and being movable upon rotation of one dial member to release an adjacent dial member for purpose of computation, and means in addition to said detent means for preventing rotation of said released dial member other than as required for computation, said latter means including a rockable lever having tooth-like projections at opposite ends, each projection being adapted for interlocking connection with a respective adjacent dial member.

5. In a calculator, in combination, a case, a plurality of at least three dial members having successive degrees of computing significance rotatably mounted in said case, and means movably mounted adjacent said dial members cooperative therewith to effect computation, said means including detent means for interlockingly connecting said plurality of dial members in positions of rest and being movable upon rotation of any dial of lower degree of computing significance to release for purpose of computation all dials of higher degree of computing significance, and interlocking means in addition to said detent means for preventing rotation of detent released dials other than as required for computation.

6. In a calculator, in combination, a case, a plurality of at least three dial members having successive degrees of computing significance rotatably mounted in said case, and means movably mounted adjacent said dial members cooperative therewith to effect computation, said means including detent means for interlockingly connecting said plurality of dial members in positions of rest and being movable upon rotation of any dial of lower degree of computing significance to release for purpose of computation all dials of higher degree of computing significance, and means in addition to said detent means for preventing rotation of detent released dials other than as required for computation, said latter means including an individual, movable member for each adjacent pair of dial members, said movable members being each adapted for selective mutually exclusive interlocking connection between the dials of its associated pair thereof.

7. In a calculator, in combination, a case, a plurality of at least three dial members having successive degrees of computing significance rotatably mounted in said case, and means movably mounted adjacent said dial members cooperative therewith to effect computation, said means including detent means for interlockingly connecting said plurality of dial members in positions of rest and being movable upon rotation of any dial of lower degree of computing significance to release for purpose of computation all dials of higher degree of computing significance, and means in addition to said detent means for preventing rotation of detent released dials other than as required for computation, said latter means including an individual rockable lever disposed generally between each pair of adjacent dials and having tooth-like projections at opposite ends for interlocking connection with respective dial members.

8. In a calculator, in combination, a case, a plurality of dial members having successive degrees of computing significance rotatably mounted in said case, each dial member having a transfer finger and a peripherally notched portion including a gear portion provided with a predetermined number of teeth, an idler gear rotatably disposed between each pair of adjacent dials, each idler gear having teeth enmeshed with the gear portion of its associated dial of higher degree of computing significance and engageable by the transfer finger of its associated dial of lower degree of computing significance, and an individual movable member for cooperation with each idler gear and the dial member of lower degree of computing significance associated therewith, each of said movable members being adapted for mutually exclusive interlock-

ing engagement with the particular idler gear and dial member directly associated therewith.

9. In a calculator, in combination, a case, a plurality of dial members having successive degrees of computing significance rotatably mounted in said case, each dial member having a transfer finger and a peripherally notched portion including a gear portion provided with a predetermined number of teeth, an idler gear rotatably disposed between each pair of adjacent dials, each idler gear having teeth enmeshed with the gear portion of its associated dial of higher degree of computing significance and engageable by the transfer finger of its associated dial of lower degree of computing significance, a rocking lever for each idler gear, said levers having tooth-like projections at each end and being pivotally mounted so as to enable selective interlocking engagement of each with either the teeth of its respective idler gear or the peripherally notched portion of the adjacent dial member of lower degree of computing significance.

10. In a calculator, in combination, a case, a plurality of dial members having successive degrees of computing significance rotatably mounted in said case, each dial member having a radially extended transfer finger and a peripherally notched portion, said latter portion comprising a cam portion provided with peripherally spaced notches surmounting a gear portion provided with a predetermined number of teeth, there being an identical notch in identical positional relationship to each of said teeth and an elongated notch between two adjacent identical notches and in predetermined positional relationship to said transfer finger, an idler gear rotatably disposed between each pair of adjacent dials, each idler gear having teeth enmeshed with the gear portion of its associated dial of higher degree of computing significance and engageable by the transfer finger of its associated dial of lower degree of computing significance, and a rocking lever for each idler gear, each of said levers having tooth-like projections at each end and being centrally pivotally mounted so as to enable one tooth-like projection to be selectively inserted between adjacent teeth of the directly associated idler gear and the other tooth-like projection to be alternatively inserted into one of the notches of the directly associated dial, the positional relationship between the said elongated notch and the transfer finger being such that the said other tooth-like projection is received in the elongated notch as the transfer finger engages and moves its associated idler gear.

11. The combination of claim 10 wherein the tooth-like projections have angularly related faces to facilitate the transfer to the levers of rocking impetuses from the intermittently engaged idler gears and cam portions.

12. In a calculator, in combination, a case, a plurality of dial members having successive degrees of computing significance rotatably mounted in said case, each dial member having a radially extended transfer finger and a peripherally notched portion, said latter portion comprising a gear portion provided with a predetermined number of teeth, one of said teeth including a section of short depth, said one tooth being in predetermined positional relationship to said transfer finger, an idler gear rotatably disposed between each pair of adjacent dials, each idler gear having teeth enmeshed with the gear portion of its associated dial of higher degree of computing significance and engageable by the transfer finger of its associated dial of lower degree of computing significance, and a rocking lever for each idler gear, each of said levers having tooth-like projections at each end and being centrally pivotally mounted so as to enable one tooth-like projection to be selectively inserted between adjacent teeth of the directly associated idler gear and the other tooth-like projection to be alternatively inserted between adjacent teeth, except the tooth having a section of short depth, of the gear portion of the directly associated dial, the positional relationship between the said tooth having a section of short depth and the transfer

finger being such that the said other tooth-like projection passes over the section of short depth as the transfer finger engages and moves its associated idler gear.

13. The combination of claim 12 wherein the tooth-like projections have angularly related faces to facilitate the transfer to the levers of rocking impetuses from the intermittently engaged idler gears and gear portions.

14. In a calculator, in combination, a case, a plurality of dial members having successive degrees of computing significance rotatably mounted in said case, each dial member having a transfer finger and a peripherally notched portion including a gear portion provided with a predetermined number of teeth, an idler gear rotatably disposed between each pair of adjacent dials, each idler gear having teeth enmeshed with the gear portion of its associated dial of higher degree of computing significance and engageable by the transfer finger of its associated dial of lower degree of computing significance, detent mechanism adapted for simultaneous interlocking connection with the several dial members for restraining them against inadvertent rotation, said detent mechanism being movable upon rotation of any dial of relatively low degree of computing significance in a manner to release its restraint upon all dials of higher degree of computing

5
10
15
20

significance, and an individual movable member for co-operation with each idler gear and the dial member of lower degree associated therewith, each of said movable members being adapted for mutually exclusive interlocking engagement with the particular idler gear and dial member directly associated therewith whereby each of the dial members released from the influence of the detent mechanism is prevented from rotation other than in accordance with corresponding rotation of the dial

10 member of next lower degree of computing significance.

15. The combination of claim 14, wherein the notched portion of each individual dial member is formed to enforce a locked condition of the dial member of next higher degree of computing significance during rotation of the individual dial member through at least part of each angular increment equal to the angular spacing of teeth on the gear portion, except the particular angular increment during which the transfer finger engages the teeth of the idler gear.
